RELEASE PLATE FOR A SAFETY SKI BINDING

Ulrich Gertsch, Matten, and Hans Eichenberger, Stuck-
ishaus, Switzerland, assignors to Gertsch A.G., Wen-
gen, Switzerland

Filed May 17, 1973, Ser. No. 361,214

Claims priority, application Switzerland Jan. 12, 1973

Term of patent 14 years

Int. Cl. D21—01

U.S. Cl. D34—14 D

FIG. 1 is a perspective view of a release plate for a safety ski binding, showing our new design;

FIG. 2 is a top plan view thereof;

FIG. 3 is a bottom plan view thereof;

FIG. 4 is a side elevational view thereof;

FIG. 5 is a front elevational view thereof; and

FIG. 6 is a rear elevational view thereof.

We claim:

The ornamental design for a release plate for a safety ski binding, as shown.
